UNITED STATES PATENT OFFICE

ANDREW P. TALLMADGE, OF WASHINGTON, DISTRICT OF COLUMBIA

CABLE ARMOR CUTTER

Application filed February 8, 1932. Serial No. 591,697.

The object of this invention is to provide a tool or implement for cutting a commercial type of spirally wound armor for electric wires or conductors, and for other purposes.

5 A further object is to provide a tool by means of which the armor may be cut or slotted longitudinally for a sufficient distance to permit of the subsequent separation of adjacent portions manually or mechanically.

10 merely—this distance being usually that required to cut two spirals or convolutions in one operation of the lever referred to below.

A further object is to provide an implement by means of which the armor is first firmly gripped between opposing jaws, and immediately thereafter is slotted or slit longitudinally, the two steps being the result of a single movement of the operating lever which carries a knife for producing the cutting stroke.

15 A further object is to provide for an eccentric movement of the cutting edge.

A further object is to limit the movement of the knife, in order to avoid damage to the insulation, if the armor incloses a conductor.

20 A further object is to provide adjusting means for one of the jaws, termed the stationary member, and to control the other jaw by a cam movement of the end portion of the lever.

25 With the foregoing and other objects in view, the invention consists in the novel construction and arrangement of elements disclosed, and in the method herein set forth,—it being understood that changes or alterations may be made within the scope of the claims without departing from the spirit of the invention.

30 In the accompanying drawings,

35 Figure 1 is a view of the tool in side elevation, with the ends of the handles broken away.

Figure 2 is a view in vertical longitudinal section, similar portions being broken away.

40 Figure 3 is also a vertical longitudinal section, the lower armor-clamping jaw having been raised by causing the operating lever or handle to assume the position shown in this view, and the knife being in operative position.

Figure 4 is a horizontal section, on line 4—4 of Figure 3.

Figure 5 is a vertical section on line 5—5 of Figure 3.

Figure 6 is a detail view, showing the upper armor-clamping member in top plan.

Figure 7 is a detail view showing the end of the lever carrying the cutter.

Figure 8 is a perspective view of the main frame in inverted position.

Figure 9 shows a length of armor after having been slotted by the tool, and after the latter has separated or severed the metallic structure, without displacing the abutting ends.

Figure 10 shows the detached sections of the armor, after separation thereof.

It is a common practice to cut armor of this type with a hack saw, and sometimes by the use of other means involving a still more crude procedure. A number of strokes with a saw are required, and the workman may often be under the necessity of resting the armor against his knee or thigh, in executing an unsatisfactory job, always involving the expenditure of time, as distinguished from the present method of doing the work instantly and without the possibility of personal injury or damage to the conductor, if the latter has previously been inserted in the tube.

In carrying out the invention, I employ a main frame 10, such as that shown in Figure 8 and elsewhere, this frame being formed on or connected with a handle 11, and flanged reinforcing means being provided at 11' and 12. The frame includes end portions 13, 13' of yoke form, and a connecting element 14, which in Figures 1 and 2 appears at the top of each view. An operating lever is mounted by means of a pivot screw or the like passing through elements 11' and 12, the lever being designated 15 and the pivot being shown at 16.

The lever 15 is provided with a cam end 17 which should be approximately of the proportions illustrated, and a knife or cutter 18 is held within a slot 19 by means of a pin or rivet 20. The form of the cutter is also important, and likewise the position of the

cutting edge with reference to that portion of the cam 17 which directly contacts with a movable clamping jaw 21. The drawing shows that the cam has hub-like relation to the cutter.

This jaw 21 is slotted longitudinally, at 21' for the accommodation of the knife and the jaw includes lugs 22 cooperating with lugs 23 on the main frame, whereby the jaw is limited in movement, but allowed to float so that it may be thrown by cam 17 into positive engagement with the armor, when the tool is positioned for use. The lugs 23 are therefore to be considered as stops, but as the element clamped also determines the extent of movement of jaw 21, members 23 serve, when the tool is not in active use, to prevent displacement or loss of the floating member.

Both jaws are to be grooved transversely in approximately the manner shown, the grooves conforming, if desired, to the adjacent portions of the spirals of the armor, and under these circumstances there can be no danger that the armor will slip or move in a longitudinal direction during the cutting operation. The cam action is also an important part of the clamping function.

The upper jaw 25 is slotted transversely at 25' and a plate 26 retained for instance by a screw 27, serves to hold the heads of screws 28 within the grooves, the jaw being retained in an adjusted position by nuts 29 engaging the threaded portions of the screws.

It is obvious that the upper jaw may be adjusted and then held in a fixed position, providing for variation in size of the armor.

Upper and lower outer plates 30, 31, secured to the main frame, extend alongside of the jaws, and are removable, thus affording access to the elements mounted within the frame per se. On the opposite side of the frame a slideable plate 33 is held by friction (or otherwise) within or inwardly from lugs 34, and the lower portion of the plate may be deflected outwardly to provide means for manipulation. This plate 33 also serves as a cover plate or closure. Figure 5 shows that the ends of the screws 28 are slotted, for engagement by a tool when adjustment of the upper jaw is being made.

The armor to be cut is surrounded by the tool, or by the yokes 12, 13' of the frame, and using one hand only for the direct cut, the workman throws lever 15 from right to left (Figures 1, 2, 3), cam 17 first engaging the lower jaw and raising the latter to clamping position, and a continuation of the same stroke of the lever moves the knife or cutter 18 to operative position. The cutter thus passes through the wall of the armor and cuts not less than two turns of the spiral, as in Figure 9, completely severing the continuous metallic structure, although the abutting ends remain connected by reason of the overlap-

ping relation of the spiral elements or individual turns or convolutions. The armor is then readily separated by hand, or under special conditions may be separated mechanically, as by the use of an implement of any suitable type.

The foregoing description of the operation of the device constitutes also a complete presentation of the method of severing or cutting the armor at any point desired, as distinguished from the methods or mode of procedure previously employed.

What I claim is:

1. In a device of the class described, elements for receiving and clamping a length of cable armor therebetween, one of these elements having an opening therein, a cutting element for slotting the armor longitudinally, the cutting element being movable through the opening, and unitary means for throwing the cutting element and the element having said opening into operative position successively by a single stroke of said means.

2. A structure comprising the elements of claim 1, the elements first named constituting opposing clamping jaws, one of which is floating, and the other of which is adjustable.

3. A structure comprising the elements of claim 1, in which said unitary means for throwing the cutter includes a cam having hub-like relation to the cutter, the cam and cutter being movable about the same axis, and the cam engaging the element having the opening for the cutter.

4. In a device of the class described, a frame, means for supporting the frame, opposing jaws mounted in the frame, a cutting blade movable into the work when the latter is clamped by the jaws, and operating means for mounting and actuating the blade, the operating means engaging one of the jaws and effecting the clamping movement thereof, before producing the cutting operation.

5. In a device of the class described, a frame, means for supporting the frame, opposing jaws mounted in the frame, means for moving one of the jaws toward the other, for clamping the work, and a cutter carried by the jaw operating means, for cutting into the work so clamped, and movable to operative position by continuing the movement of said means serving to throw one jaw to active position with reference to the other and to the work.

6. A structure comprising the elements of claim 4, the working faces of the jaws being grooved.

7. A structure comprising the elements of claim 4, the movable jaw being slotted, and the blade passing through the slot of this jaw.

In testimony whereof I have affixed my signature.

ANDREW P. TALLMADGE.
